Primary Examiner — Philip S Hyder

(74) *Attorney, Agent, or Firm* — Merchant & Gould P.C.

(57) **CLAIM**

The ornamental design for a screwdriver, as shown and described.

DESCRIPTION

FIG. 1 is a perspective view of a screwdriver showing my new design;

FIG. 2 is a left-side elevation view thereof;

FIG. 3 is a right-side elevation view thereof;

FIG. 4 is a top plan view thereof;

FIG. 5 is a bottom plan view thereof;

FIG. 6 is an enlarged front elevation view thereof;

FIG. 7 is an enlarged rear elevation view thereof; and,

FIG. 8 is an enlarged perspective view of a front portion thereof.

The portions shown in broken lines form no part of the claimed design.

1 Claim, 5 Drawing Sheets
